HARNESS

Thomas E. Jackson, Zanesville, Ohio, assignor, by
mesne assignments, of one-half to The Glyde-
Rite Corp., Zanesville, Ohio, a corporation of
Ohio

Application October 9, 1947, Serial No. 778,944

4 Claims. (Cl. 54—71)

1

This invention relates to harness, and more particularly to an improved hopple for controlling the gait of pacing horses.

Heretofore it has been the practice to make such hopples of leather or from rawhide. However, such construction has not been entirely satisfactory since such hopples require the use of special materials, such as calfskin and the like, for covering the leg rings to prevent chaffing. Also, such hopples generally require padding around the neck strap to prevent slipping as well as chaffing. It is also necessary with such hopples to use relatively heavy straps having sufficient strength to withstand the sudden shock or strain imparted to the hopple when the horse lunges or breaks its gait. Thus the leather or rawhide must be heavy enough to withstand and absorb the sudden shock caused by such action on the part of the horse. Such action, however, in due time permits the leg rings to stretch, and the hopple starts to sag or swing up and down and no longer rides straight and smoothly on the horse's sides and withers, which further tends to encourage the horse to break.

Another defect or fault in present hopples is caused by the relatively rough surface of the leather tending to pull the hair around the horse's legs, withers and sides, which irritates the skin. The heat and friction from the rubbing of the hopple then tends to further irritate or burn the skin which, in time, may become infected and sore. This condition is aggravated by the fact that the leather is generally toxic due to the absorbing of sweat and dirt which is ground into the leather and cannot be removed easily.

A further defect in the use of leather hopples arises from their tendency to turn, twist and crack, particularly in cold weather, which in addition to making it difficult to handle prevents it from conforming properly to the sides and withers of the horse whereby further chaffing and rubbing results.

One of the objects of the present invention is to overcome the above noted defects and to provide an improved hopple which is lighter in weight and stronger than present hopples, which follows the horse's stride by riding in a substantially straight line when the horse is pacing, and which is so balanced in weight between the leg rings and the adjusting straps connecting therebetween as to prevent bowing out when the horse is pulling, or sagging when the hopple is wet, or even after it has been used for a relatively long period of time.

2

Another object is to provide a substantially lighter weight hopple than can be constructed of leather, which is strong enough to withstand safely the required shock and strain normally imparted to a hopple, which does not tend to rub, chaff or pull hair, and which does not pick up and carry moisture, dirt and sweat, and thereby facilitates the maintenance of the hopple in a clean and nontoxic condition.

10 It is also an object to provide a hopple which will wear longer and can be manufactured substantially cheaper than leather by a forming process which eliminates the necessity for hand-work, such as lacing and stitching, and which can be constructed in various bright and nonfading colors of extruded pieces of resinous material connected by heat sealing to form substantially continuous one piece members with sections having a predetermined shape or form along the surface contour in contact with the hide which is adapted to prevent rubbing, chaffing and pulling of hairs.

15 A further object is to provide a safer, light-weight hopple having smooth, straight and evenly balanced riding qualities, which is adapted to overcome breaking on the part of the horse, and which has the adjusting strap connecting the leg rings formed as an integral part of one of the rings and thereby requiring only a single buckle for 20 adjustment, the weight of the leg rings and adjusting strap being varied with respect to each other so as to balance and ride without sagging.

An additional object is to provide an improved hopple of the character described in which the 25 leg rings and connecting straps are constructed of substantially lighter weight pieces of molded plastic which provide a balanced weight whereby better riding qualities are obtained, which does not change even when wet, or after long periods of use, and which does not pick up and carry dust and dirt particles as does the usual leather hopple.

Still another object is to provide a hopple of 30 plastic material which cannot rot or otherwise deteriorate to any determinable extent from being subjected to heat, moisture and sweat, which does not require oils or soap to maintain it in a clean, nontoxic condition, yet which presents a smooth, brightly colored and specially contoured flexible 35 surface free of any tendency to chaff the skin or pull hair, and which can be formed with the uprights for the carrying straps, supporting members and leg ring spreaders as an integral part of the hopple without requiring stitching or lacing 40 therefor.

Also another object is to provide a halter in which the mid-portion has sufficient elasticity to absorb the shock of a hard pacing stride without throwing the horse off gait.

Other objects and advantages of this invention will be apparent from the following description, the appended claims, and the accompanying drawings wherein a preferred form of one embodiment of the present invention is shown.

In the drawings:

Fig. 1 is a view in perspective showing a halter constructed in accordance with the present invention;

Fig. 2 is a plan view on an enlarged scale of the front and hind leg rings and adjusting strap on one side of the halter shown in Fig. 1;

Fig. 3 is a view on an enlarged scale partially in vertical section and in elevation taken substantially on the plane 3—3 of Fig. 2.

Fig. 4 is a view similar to Fig. 3 taken substantially on the plane 4—4 of Fig. 2; and

Fig. 5 is a view also similar to Fig. 3 taken substantially on the plane 5—5 of Fig. 2.

Referring further to the drawings, the halter illustrated in Fig. 1 comprises in general a pair of front leg rings 20 and 21 connected by means of the adjusting straps 22 and 23 to the hind leg rings 24 and 25. The front leg rings in turn are provided with a pair of uprights 26 and 27 to which the lower ends of the neck strap 28 are connected. On the rear portions of the front leg rings similarly formed uprights 31 and 32 are provided to which are attached the free ends of a carrying strap 33 which is adapted to fit over the back of the horse. The adjusting straps 22, 23 are also provided with uprights 34 and 35 to which the free ends of the carrying strap 36 are fastened. Uprights 37 and 38 forming a part of the hind leg rings 24, 25 are in turn connected to the rear carrying strap 41.

In constructing this halter it has been found that to secure an even and balanced ride with respect to the front and hind leg rings and their adjusting strap, and to secure the other advantages and features heretofore mentioned, the halter as described can best be formed from a plastic material, such as the vinyl resin, for example, which is sold under the trade-name "Geon." This material can be colored as desired and extruded in the form of straps of the proper weight and dimensions, having as well a predetermined form of surface contour, to provide a halter of the character described. It is to be understood, however, that other types of plastic material providing these characteristics can be used if desired.

In forming one of the front leg rings, 21 for example, the plastic material is extruded in the form of a one-piece strap 29, Fig. 3, the inner surface of which is smoothly curved, and which is sufficiently flexible to be bent in the shape of a loop substantially as shown in Fig. 2. The ends of strap 29 are folded over to form a closed loop 30 in which the connecting ring 42 is inserted. Upright or tab 31, with its connecting buckle 43 already attached, is also inserted with its lower end sealed within the closed loop 30 to position and hold it securely. The free ends of strap 29 are then heat sealed to form a smooth strong joint, as at 44, which provides a substantially continuous one-piece leg ring. Upright or tab 27 is also secured to the front leg ring by heat sealing it to the upper surface as shown in Fig. 3. If it is desired to additionally reinforce the uprights a substantially triangular shaped wedge member 45 is sealed in position along the base

of the upright and against the upper surface of the leg ring. A spreader 46 of similarly formed plastic material can be positioned across the interior of the open loop 47 to hold the leg ring in a substantially extended or open position if such is desired. The other front leg ring 20 is similarly formed.

The hind leg ring and adjusting straps, 23 and 25 for example, can be formed also from a single strap of extruded plastic material. It is preferred, however, to form them as separate members the free ends of which are later connected as by means of a heat seal, as at 48, to provide a continuous and substantially one-piece combined leg ring and adjusting strap. The uprights 35 and 37 are secured in position and reinforced if desired, as previously described in connection with the uprights 27 and 31 and as illustrated at 45. A buckle 49 is then connected to the free end of the strap 50 forming the hind leg ring. This buckle receives the free end of the strap 51 after it has been passed through the connecting ring 42 in the form of a flat or closed loop to provide the necessary adjustment in the usual manner. Slidable plastic loops 52 and 53 are provided to retain the loose or free end of strap 51 in the usual manner after the adjustment is made. A fixed loop 54 is also provided for the closed loop portion. This loop is retained in position close to ring 42 by means of a short strip 55 of plastic sealed at one end to the loop 54 and at the other end to the inner surface of the front leg ring 21. Hind leg ring and strap 22 and 24 are similarly constructed. The hind leg rings 24 and 25 can also be provided with a spreader 46 if desired, as previously described, which is positioned across the loops to hold them in an open position substantially as shown.

In forming the straps for the front and hind leg rings it is preferred that they be provided with a central core comprising a single piece of steel wire 60, Figs. 2 and 3. This wire has a substantially circular cross section and is of about #10 gauge in weight. The wire forms a stiffener which helps to provide for holding both the front and hind leg rings in their proper shape after they are formed, prevents their sagging, and also serves to control any expansion of the plastic which tends to take place when heat is applied thereto, and limits any such to a minimum. Wire 60 also facilitates holding the leg rings in position to obtain balanced riding qualities. Also in forming the strap of which the front and hind leg rings are constructed, it is to be noted that the inner surface of the ring, as shown for example in Fig. 3 and which is the surface contacting the hide of the horse's legs, is constructed to provide a smoothly curved surface contour as at 63 which is preferably substantially oval in shape as shown.

To secure the proper balance and riding qualities, the combined weight of the front and hind leg rings should be substantially equal to the weight of the adjusting strap connecting therebetween together with the buckle and strap loops. To provide for this balance the leg rings are constructed so that their vertical height, as measured in a vertical plane between the points 64 and 65 in Fig. 3, is approximately $\frac{5}{8}$ of an inch. The thickness of the leg ring straps, as measured along a horizontal plane between the points 66 and 67, is then made approximately $\frac{3}{8}$ of an inch. To compensate for the additional weight of the buckle 49 and the loops 52, 53 and 54 the weight of the adjusting strap portion 23 is con-

trolled by decreasing the thickness of each strap, as measured in a horizontal plane between the points 68 and 71, Fig. 5, to $\frac{1}{4}$ of an inch approximately while the vertical height remains substantially $\frac{1}{8}$ of an inch. The adjusting strap portion being thinner in cross section is lighter in weight than either of the leg rings. For example, in one form the front leg ring may weigh approximately 8 ounces and the adjusting strap 6 ounces. Where the hind leg ring is made about 2 inches longer than the front leg ring, its weight, including the stiffening wire 60 may be as much as 16 ounces. However, it is preferable that the combined weight of the front and hind leg ring is made substantially equal to the weight of the connecting adjusting strap, together with the buckle and the loops, which provides for a smooth and balanced riding quality which cannot otherwise be obtained.

It is to be noted also that with the above described construction the hopple has a mid-portion between the front and hind leg rings formed to provide sufficient elasticity to absorb the shock of a hard pacing stride without throwing the horse off gait.

From the above description it will be apparent that there is provided a strong, light weight and weatherproof hopple for controlling the gait of a horse which is so constructed and balanced in weight as to follow the stride in a substantially straight line when the horse is pacing. Furthermore this hopple is constructed of a material which can be kept in a sanitary and nontoxic condition with a minimum of effort and time, and which is formed to present a curved surface in contact with the hide which is so smooth as to prevent the rubbing or chaffing of the skin and the pulling of hair.

While the forms of embodiments of the present invention as herein disclosed constitute preferred forms, it is to be understood that other forms might be adopted, all coming within the scope of the claims which follow.

I claim:

1. In a hopple for controlling the gait of a horse, a front leg ring formed of plastic mate-

rial, a combined one-piece hind leg ring and adjusting strap formed of plastic material connected to said front leg ring, and supporting tabs connected thereto for attaching to carrying straps, said tabs having reinforcing webs extending along the lower part thereof to provide additional support therefor.

2. In a hopple for controlling the gait of a horse, a plastic front leg ring, a plastic hind leg ring, and a plastic adjusting strap connecting between said front and hind leg rings, said leg rings having a combined weight substantially equal to that of said strap to provide a balanced riding quality.

3. In a hopple for controlling the gait of a horse, a plastic leg ring, and a combined leg ring and adjusting strap formed of plastic material connected to the first said leg ring, the ends of said combined leg ring and strap being fastened by means of a buckle, said leg rings having a sufficiently greater thickness than said strap to provide a combined weight thereof substantially equal to that of the strap and buckle, the leg rings and strap thereby providing a balanced riding quality.

4. In a hopple for controlling the gait of a horse, a plastic front leg ring, a plastic hind leg ring said front and hind leg rings having a wire core formed therein, and a plastic adjusting strap connecting between said front and hind leg rings, said leg rings having a combined weight substantially equal to that of said strap to provide a balanced riding quality.

THOMAS E. JACKSON.
